CLAIM

I claim the ornamental design for an incubator for animal, as shown and described.

DESCRIPTION

FIG. 1 is a perspective view of an incubator for animal showing my new design;

FIG. 2 is a front elevational view thereof;

FIG. 3 is a rear elevational view thereof;

FIG. 4 is a left side elevational view thereof;

FIG. 5 is a right side elevational view thereof;

(Continued)

FIG. 6 is a top plan view thereof; and,
FIG. 7 is a bottom plan view thereof.

1 Claim, 6 Drawing Sheets
